[57] CLAIM

The ornamental design for a writing instrument, sub-
stantially as shown and described.

DESCRIPTION

FIG. 1 is a front elevational view of a writing instru-
ment showing my new design, shown with the writing
point extended;

FIG. 2 is a front elevational view similar to FIG. 1,
shown with the writing point retracted;

FIG. 3 is a right side elevational view thereof;

FIG. 4 is a rear elevational view thereof;

FIG. 5 is a top plan view thereof;

FIG. 6 is a bottom plan view thereof; and

FIG. 7 is a perspective view thereof.
